CLAIM

The ornamental design for a process monitoring controller, as shown and described.

DESCRIPTION

FIG. 1 is a front, top and right side perspective view of a process monitoring controller, showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof;

FIG. 8 is an enlarged cross-sectional view, taken along the line 8—8 of the process monitoring controller with its internal mechanisms omitted; and,

FIG. 9 is an enlarged cross-sectional view, taken along the line 9—9 of the process monitoring controller with its internal mechanisms omitted.
